UNITED STATES PATENT OFFICE.

FRANK E. SCHMIDT, OF PHILADELPHIA, PENNSYLVANIA.

SUSPENSION-SUPPORT FOR HAMMOCKS.

No. 820,605.

Specification of Letters Patent.

Patented May 15, 1906.

Application filed January 19, 1906. Serial No. 296,762.

To all whom it may concern:

Be it known that I, FRANK E. SCHMIDT, a citizen of the United States, residing at the city of Philadelphia, in the county of Philadelphia and State of Pennsylvania, have invented certain new and useful Improvements in Suspension-Supports for Hammocks, of which the following is a specification.

My invention has relation to a suspension-support for hammocks and other appliances; and in such connection it relates particularly to the construction and arrangement of a bracket for supporting suspended a hammock or other appliance.

15 The principal objects of my invention are, first, to provide a bracket for supporting suspended a hammock and arranged to permit of ready connection of the same with the ceiling of a house, the roof of a porch, or any 20 other suitable elevated structure; second, to provide a bracket for such purpose with detachable braces to assist in the support of the same and to take up side thrust to which the bracket may be subjected by—for example, 25 the hammock supported in a suspended condition therefrom—and also to permit of connection of the braces with uneven surfaces of the supporting structure, and, third, to provide a bracket for such purpose with means 30 to permit of ready connection and disconnection of braces to and from the same.

The nature and scope of my present invention will be more fully understood from the following description, taken in connection 35 with the accompanying drawings, forming part hereof, in which—

Figure 1 is a view illustrating in side elevation, a bracket connected with the ceiling of a house or roof of a porch having detachable 40 braces connected therewith and ceiling or porch-roof and with arms carrying a hammock in a suspended condition from the bracket. Fig. 2 is a view, enlarged, illustrating, partly in side elevation and partly in section, the bracket, a yoke pivotally connected therewith, and also showing certain portions 45 of the hammock-support. Fig. 3 is a sectional view on the line 3 3 of Fig. 2; and Figs. 4 and 5 are detail views, enlarged, illustrating 50 in elevation braces of varying length employed in said bracket.

Referring to the drawings, *a* represents a bracket terminating at one end in a disk *a'* and at its other end in a forked portion *a''*, 55 preferably formed integral therewith. The disk *a'* is provided with openings *a''* for the

reception of screws or bolts, (not shown,) by means of which the bracket *a* is secured to the ceiling of a house, the roof of a porch, or any other suitable elevated structure *a''*. Between the disk *a'* and forked portion *a''* the bracket *a* is provided with ribs *b*, having hook-like projections *b'* and *b''* and a slot *b''*, separating the projections from each other. In the present instance to the forked end *a''* of the bracket *a* by means of a bolt *a''* is pivotally secured a yoke *c*, preferably forked at its downwardly-projecting ends *c'*. To these forked ends *c'* are secured, by means of bolts *c''*, the ends *d'* of the arms *d*, provided with 70 sockets *d''*, each socket having eyes *d''* and *d''* at its upper side and a hook *d''* at its lower side, as shown in Fig. 1. Through the eye *d''* of each of the sockets *d''* is passed a chain *e*, secured to the ceiling *a''* by a hook *e'*. The 75 chains *e* may be lengthened or shortened by means and in a manner not shown, and thus the arms *d* may be held by the chains *e* at their free ends in any desired position with respect to the ceiling *a''*. To the hooks *d''* of 80 the sockets *d''* are secured the cords *f'* of a hammock *f*, which is thus suspended from the ends of the arms *d* and is held by the same preferably in the position shown in Fig. 1. The weight of the hammock *f* and of a 85 person occupying the same is partially taken up by the chains *e* and through the intervention of the arms *d* and yoke *c* is transmitted to the bracket *a*.

The chains *e* being flexible do not resist side 90 thrust, to which the same are subjected by the movement of the hammock *f*. This side thrust is solely borne by the bracket *a*, which for such purpose is strengthened by braces *g*, constructed and arranged in the following preferred manner: As shown in Figs. 4 and 5, each of the braces *g* terminates at one end in a fork *g'*, through which a bolt *g''* passes, and at its other end is provided with an opening *g''*. As shown in Fig. 1, in operative position 95 each of the braces *g*, with its forked end, overlaps certain of the hook-like projections *b'* and *b''* of the ribs *b* of the bracket *a*, while the bolt *g''* thereof engages the slot *b''* of the ribs. At the other end each of the braces *g* is preferably engaged by a bearing-plate *h*, secured 100 to the ceiling *a''*, the bolt *h'* of which passes through the eye *g''* thereof, and thus movably connects the brace *g* with the plate *h*. Each of the braces *g*, engaging the bolt *g''*, the slot 105 *b''* of the ribs *b* of the bracket *a* and by engaging the rib *b* from both sides thereof, are se-

surely yet removably connected with the same. Owing to this connection, the braces *g* will assist the bracket *a* in the support of the hammock *f* and its occupant when the 5 arms *d* occupy certain raised positions and will also take up at all times any side thrust to which the bracket *a* may be subjected by the movements of the hammock *f* and person therein, as will be readily understood 10 from Fig. 1.

In addition to taking up side thrust the braces *g* also serve to permit of the secure connection of the same to uneven surfaces of the ceiling of a home or the roof of a porch— 15 such as slanting or inclined portions thereof, cornices, projecting beams, or other extending parts in the following manner: As shown in Fig. 1, the braces *g*, being movably connected with the bracket *a* and the plates *h*, may 20 assume any angular position with respect to the same. Moreover, the braces *g*, being of varying length, the longer one thereof may be readily connected, for instance, with an upwardly-inclined portion of the roof of a 25 porch, while the shorter braces may be employed to connect the bracket *a* with a straight or horizontal portion thereof. In case a projecting beam is to be utilized for the support of the bracket *a* the long braces 30 *g* (shown in Fig. 4) may be used to connect the bracket with that portion of the ceiling of a house or the roof of a porch which is directly supported by the beam to which the bracket *a* is secured.

35 As shown in Figs. 1 and 2, the ribs *b* of the brackets *a* are provided with superposed projections *b'* and *b''* and slots *b'* to permit of the engagement of the braces *g* at different portions of the bracket *a*, if desired. In addition to the chains *e* the arms *d* are engaged 40 by cords *i*, secured to the eyes *d'* of the socket *d*, which by passing over pulleys *k*, carried by the hooks *e'*, permit of the raising of the arms *d* and hammock *f* into an inoperative 45 position close to the ceiling *a'* and of the holding of the same in this position. The arms *d* may be directly secured to the bracket *a*. However, the yoke *c*, carrying the arms

d at their point of junction, permit of a certain movement in the bracket *a*. 50

Having thus described the nature and objects of my invention, what I claim as new, and desire to secure by Letters Patent, is—

1. A support for hammocks, &c., consisting of a bracket, a support from which said bracket is suspended, and means connecting said bracket with said support and arranged to assume varying angular positions thereto. 55

2. A support for hammocks, &c., consisting of a bracket, a support from which said bracket is suspended, and means arranged to connect said bracket with portions of said support, differing in elevation and in angular position with respect to said support. 60

3. A support for hammocks, &c., consisting of a bracket, means connected with said bracket forming hooks, an elevated support from which said bracket is suspended, and braces engaging said hooks and said elevated support and arranged to assume varying angular positions to said bracket. 65 70

4. A support for hammocks, &c., consisting of a bracket provided with strengthening-ribs having slots formed therein, an elevated support from which said bracket is suspended and braces having forked ends for engaging said ribs and for connecting the same with said support. 75 80

5. A support for hammocks, &c., consisting of a bracket provided with strengthening-ribs having slots formed therein, an elevated support from which said bracket is suspended, braces having forked ends, a bolt arranged in said forked ends, the forked end of each of said braces arranged to engage a rib of said bracket from opposite sides and to hold the bolt in engagement with the slot thereof and said braces adapted to connect said bracket with said support. 85

In testimony whereof I have hereunto set 90 my signature in the presence of two subscribing witnesses.

FRANK E. SCHMIDT.
